SEAT MUTILATION SIGNAL SYSTEM

Filed March 7, 1949

UNITED STATES PATENT OFFICE

2,560,268

SEAT MUTILATION SIGNAL SYSTEM

Harold J. Ballam, New Orleans, La.

Application March 7, 1949, Serial No. 80,012

2 Claims. (Cl. 177—311)

1

My invention relates to a detector and alarm system for use with chairs and seats, and is intended to give a signal near a chair or seat when the same is being defaced or destroyed. This occurs perhaps most often in moving-picture houses of the cheaper class where patrons cut the upholstery of seats with knives. No satisfactory way of dealing with such vandalism has been found, though various expedients have been tried, e. g., private detectives, who are, however, expensive and not very effective in preventing such damage.

Another object of my invention is to provide simple signaling means of the character described, which shall be effective on a larger number of seats, and in the use of which a single person, or a small number of persons, can observe the signals for a large number of seats.

Another object is to provide signaling means of the character described, in which the signal shall continue in action after the vandalism has stopped, as where a boy thrusts his knife through a seat cushion and then immediately withdraws it and does not repeat the operation.

Referring to the annexed drawings, which are made a part of this application and in which similar reference characters indicate similar parts:

Fig. 1 is a perspective of a row of seats equipped with the device of my invention, and

Fig. 2 is an enlarged front elevation, with the seat partly broken away.

In the drawings, reference character 10 indicates a seat or chair such as commonly used in theaters, it being understood that any conventional or preferred seat may be used, so long as it is otherwise adapted to have my invention applied to it. Several chairs with independent seats are usually but not necessarily arranged in a row as shown.

The chairs are shown as being seats here shown as fixed and comprising cushions that may be padded at 11 and covered with upholstery 12. Inside the cushion and preferably parallel to but spaced from the top upholstery 12 and the bottom supporting layer 13 there are two sheets 14 and 15 of screen wire or any suitable material to serve for conducting electricity. The screens extend preferably from side to side and from front to rear of each cushion, so that any stab or cut of substantial depth will strike both of them and connect them electrically if made by a knife blade or like object.

A layer 16 of insulating material is interposed between the screens, this layer being preferably

2

quite thin so as to offer but little resistance to a cutting or stabbing implement. Usually both screens 14 and 15 and sheet 16 should be close to the top and sides of the cushion so that a cut of any substantial depth will be sure to operate the signal or signals.

Conductors 17 and 17' are connected to the respective screens. In the form of the invention at present preferred, I have shown an electric signal lamp 18 at the back of each chair, a signal lamp 19 at the aisle end of a row of chairs, and another signal lamp or an audible signal (or both) are preferably provided at a suitably remote point, as in the manager's office.

The conductor 17 extends to a holding circuit comprising a relay 21 and a switch 22, the winding of the relay continuing through bulbs 18 and 19 and electromagnet 23 and then to transformer 24 which is connected to house line 25. Operation of switch 22 by relay 21 closes a circuit through lines 26 and 17 and the connection to ground remaining intact even though that to line 17' should be broken, so that the circuit to the signals also remains closed until manually broken, as by manual operation of switch 22 or by turning off the entire system and so releasing all circuits.

It will be evident that if someone should stick a knife through a cushion, the corresponding light 18 will indicate the seat that has been cut, while the light 19 at the end of a row indicates the row in which that seat is located.

The electromagnet 23 operates a switch 27, which when moved clockwise thereby closes a circuit through line 28 to operate a light, a buzzer or other signal remote from the seats so as to notify the manager or other person in authority that a certain seat or seats are being mutilated.

It will be obvious that the device of my invention may be changed in many ways, all without departing from the spirit of the invention, and therefore I do not limit myself to what is shown in the drawings and described in the specification, but only as indicated in the appended claims.

Having thus fully described my invention, what I claim is:

1. Means for indicating mutilation of a seat cushion or the like comprising padding, and upholstery covering the top and sides of the cushion, a pair of sheets of material adapted to conduct electricity, a layer of insulation between said sheets, said sheets and said layer 55 being embedded in said cushion and lying close

to the upholstery over the top and the sides of the same, signaling means on a fixed support adjacent the cushion, and electrical connections from said sheets to said signaling means.

2. The combination of a seat, a cushion there-
fore, said cushion including padding and up-
holstery covering the padding, a pair of sheets
of electrically conductive material embedded in
the padding adjacent the upholstery, a layer of
insulation between sheets an electrically oper-
ated signal adjacent the seat, and electrical
connections from said sheets to said signal.

HAROLD J. BALLAM.
